UNITED STATES PATENT OFFICE.

GEORGE M. EATON, OF PITTSBURGH, PENNSYLVANIA, ASSIGNOR TO WESTINGHOUSE ELECTRIC AND MANUFACTURING COMPANY, A CORPORATION OF PENNSYLVANIA.

RESILIENT DRIVING CONNECTION.

1,321,511.

Specification of Letters Patent.

Patented Nov. 11, 1919.

Application filed October 14, 1916. Serial No. 125,636.

To all whom it may concern:

Be it known that I, GEORGE M. EATON, a citizen of the United States, and a resident of Pittsburgh, in the county of Allegheny and State of Pennsylvania, have invented a new and useful Improvement in Resilient Driving Connections, of which the following is a specification.

My invention relates to resilient driving connections and particularly to a flexible gear wheel for connecting the propelling motors to the driving wheels of electric railway vehicles.

One object of my invention is to provide a flexible gear wheel of the above-indicated class in which the resilient connecting means, which operatively associates the hub with the rim member, is positively insured against unintentional displacement.

Another object of my invention is to provide a resilient driving connection which shall utilize the centrifugal force of the rotating parts and the spring pressure exerted against the sides of the spring-retaining pockets for holding the springs in place.

A further object of my invention is to provide a resilient driving connection with a greater capacity for spring material, and, therefore, a greater operating range, than those heretofore proposed.

A further object of my invention is to provide a tool by which the springs may be readily removed by the application of a force in a lateral direction relative to the driving connection.

Heretofore, it has been found necessary to provide tongues on the spring seats, and co-operating grooves in the ends of the spring-retaining pockets of driving connections for preventing lateral displacement of the springs, or to equip the gear with side plates, to retain the springs in place. Such structures require expensive machining and embody a number of unnecessary parts.

My invention provides a spring seat which co-operates with a groove or flange in the rim to hold the spring in place, and the driving connection is so constructed that displacement of the spring is impossible without considerable bending of the spring.

Sheets 1 and 2 of the accompanying drawing illustrate a resilient gear wheel embodying my invention. Figure 1 is a side elevational view of the rim member; Fig. 2 is a sectional view on the line 2--2 of Fig.

1; Fig. 3 is a side elevational view of the hub member; Fig. 4 is a sectional view on the line 4--4 of Fig. 3; Fig. 5 is a side elevational view of the spring seat; Fig. 6 is an end elevational view of the spring seat; Fig. 7 is a side elevational view, with parts sectioned and broken away, of the assembled gear wheel; and Fig. 8 is a sectional view on the line VIII--VIII of Fig. 7. Sheets 3 and 4 show a tool for readily disassembling the gear wheel. Fig. 9 is a bottom plan view of the tool; Fig. 10 is an end elevational view of the tool; Fig. 11 is a sectional side view of the gear wheel showing the tool in its first operative position; Fig. 12 is a side view, partially in section and partially in elevation, of the tool applied as in Fig. 11; Fig. 13 is a sectional view of the gear and tool just prior to the removal of the spring; and Fig. 14 is a side view, partially in section and partially in elevation, of the tool in the position shown in Fig. 13.

The gear wheel shown in the drawing comprises a rim member 1, a hub member 2, and a plurality of tangentially-disposed springs 3 and spring seats 4 for resiliently connecting the hub member to the rim member. The rim member 1 is provided with a plurality of inwardly projecting radial lugs 5 and circumferential grooves 7 which are cut into the inner surface of the rim member for a purpose hereinafter set forth. The hub member 2 has outwardly extending radial lugs 6 which correspond, in angular position, to the lugs 5, are laterally spaced to admit the lugs 5 therebetween and are disposed substantially in the same planes as the grooves 7. A spring-receiving pocket is formed between adjacent sets of co-operating lugs 5 and 6 into which a spring 3 and spring seats 4 are positioned to resiliently and operatively connect the rim member 1 to the hub member 2. The springs 3 are helical in form and are held in tangential relation to the gear wheel by the spring seats 4. Each of the spring seats 4 has a flat bearing surface which engages the ends of a set of co-operating lugs 5 and 6 and one or more lugs 8 that engage the grooves 7 of the rim member 1 to prevent lateral displacement of the spring members. Each pair of the spring seats 4 is also provided with cylindrical lugs 9 which respectively extend into opposite ends of a spring 3 to position the same. The hub member 2 is

further provided with portions 10 which are of sufficient radius to engage the springs 3 just prior to the disengagement of the lugs 8 and the grooves 7. This insures that the 5 spring seats will not be displaced during the operation of the gear wheel by reason of the fact that the very heavy helical springs 3 must be bent before the spring seats 4 can become dislodged.

- 10 To assemble such a gear wheel as I have herein described, the lugs 5 of the rim member are positioned between adjacent lugs 6 of the hub member, and the rim member is partially rotated until the lugs 5 are received 15 between the laterally-spaced lugs 6 and register therewith to form spring pockets. The springs 3 and spring seats 4 are compressed and inserted into the spring pockets and, when released, the pressure of 20 the springs 3 against the spring seats 4 forces the spring seats 4 into engagement with the rim and causes the lugs 8 to enter the grooves 7 and thereby lock the springs in place. The diverging sides of the pockets 25 with which the spring seats engage and the centrifugal force of the rapidly rotating gear wheel cause the spring seats 4 to be held firmly in engagement with the rim member.
- 30 The application of a driving force to the rim 1 causes the rim member to move relatively to the hub member until the springs 3 are sufficiently compressed to resist further relative movement of the parts of the 35 gear wheel when the hub 2 will be rotated as in a solid wheel.

The spring seats may be positioned at a greater radius from the gear center in a gear wheel constructed in accordance with 40 my invention than in gear wheels that have been proposed heretofore. This permits of the use of a greater amount of spring material and, consequently, provides a gear wheel of greater operating capacity than 45 types heretofore proposed. A tool 20 has been provided with which the spring 3 may be easily and quickly removed. The tool 20 comprises a blade 21 which is curved to fit the inside of the rim 1 and is provided with 50 wedge-shaped edge portions 22 and lugs 23 which extend oppositely and outwardly from the respective bases of the wedge portions 22, and a handle 24 by means of which force is applied to the tool.

- 55 In order to remove the spring 3 from the pockets, the tip of the blade 21 is inserted between the rim member 1 and the spring 3 and forced in a lateral direction relatively to the gear wheel. The wedge-shaped edges 60 of the blade 21 force the spring seats 4 radially inward and move the lugs 8 out of engagement with the grooves 7. Just prior to the disengagement of lugs 8 with the grooves 7, the spring 3 engages the portion 65 10 of the hub, and the ends of the spring

are forced radially inward, thereby bending in the spring. After the spring 3 is sufficiently bent to permit the lugs 8 to be wholly disengaged from the grooves 7, the lugs 23 of the tool engage the spring seats 70 and force the same laterally from the gear wheel. The step in the operation just prior to the lateral movement of the spring seats is shown in Figs. 13 and 14. It will, therefore, be understood that the mere application 75 of a lateral force upon the tool 21 will first move the springs radially inwardly and subsequently engage the spring seats and move the spring structure laterally from the gear wheel.

80 Although I have set forth my invention as embodied in a simple and preferred form of resilient gear wheel, it should be understood that the invention is capable of application to a great many types of driving 85 connections and should be limited only by the spirit and scope of the appended claims.

I claim as my invention:

1. In a resilient driving connection, the combination with a hub member having laterally-spaced radial projections, and a rim member having radial projections disposed between said hub projections, said hub and rim projections being arranged in sets, with 90 pockets therebetween, of resilient means for connecting said rim member to said hub member comprising a helical spring and seats for said spring having plane bearing surfaces for engaging said springs and said radial projections.

2. In a resilient driving connection, the combination with a hub member, a rim member surrounding said hub member and having a circumferential groove therein, and co-operating radial projections on said members, of connecting means engaging said projections for resiliently joining said members, said means embodying lugs adapted to engage said groove to prevent displacement 105 of said connecting means.

3. In a resilient driving connection, the combination with a hub member having a plurality of radial projections, and an annular rim member surrounding said hub member and having annular grooves formed 110 in it and a plurality of integral radial projections co-operating with said hub projections to form pockets therebetween, of springs adapted to be inserted in said pockets to resiliently connect said rim and hub 115 members, and seats for said springs having means engaging said grooves in the rim member for preventing lateral displacement of said springs.

4. In a resilient driving connection, the combination with a hub member having a plurality of radial projections, and a rim member surrounding said hub member and having a plurality of radial projections co-operating with said hub projections to form 120 125 130

pockets therebetween, of resilient means inserted in said pockets for connecting said rim to said hub member comprising a spring and a plurality of spring seats, said rim member being provided with a single means coöperating with all of said spring seats for holding the same in place.

5. In a resilient driving connection, the combination with a hub member having laterally-spaced radial projections, and a rim member having radial projections disposed between said hub projections and an annular groove, said projections forming sets, with openings through the driving connection between said sets, of connecting means inserted in said openings for resiliently joining said hub and rim members and embodying two retaining members having ridged surfaces mating with the interior 20 surface of said rim member and engaging said groove to prevent lateral displacement of said retaining members.

6. In a resilient driving connection, the combination with a hub member having a plurality of radial projections, and an annular rim member surrounding said hub member and having two annular grooves and a plurality of integral radial projections located between said grooves and coöperating 30 with said hub projections to form pockets therebetween, of springs tangentially disposed in said pockets, and seats for said springs, said spring seats having portions thereof forced into said grooves for preventing lateral displacement of the springs.

7. In a resilient driving connection, the combination with a hub member having a plurality of radial projections, and an annular rim member surrounding said hub member and having a plurality of radial projections coöperating with said hub projections to form pockets therebetween and annular grooves located adjacent to the projections, of springs tangentially disposed in 45 said pockets, and seats for said springs, said spring seats having means concentric with said rim member and disposed in said grooves for preventing lateral displacement of said springs.

50. 8. In a resilient driving connection, the combination with a hub member having a plurality of radial projections, and an annular rim member surrounding said hub member and having a plurality of radial projections coöperating with said hub projections to form pockets therebetween, of spring tangentially disposed in said pockets, and seats for said springs, said rim member having means on the inner cylindrical surface thereof for coöperating with said spring seats to prevent lateral displacement of said springs.

9. In a resilient driving connection, the combination with a hub member having a plurality of radial projections, and an an-

nular rim member surrounding said hub member and having annular grooves formed in it and a plurality of radial projections coöperating with said hub projections to form pockets therebetween, of springs tangentially disposed in said pockets, and seats for said springs, said spring seats being provided with lugs located in the grooves of said rim member for holding said springs against lateral displacement.

10. A resilient driving connection comprising two parts having coöperating radial projections, the projections on the one part being provided with a circumferential groove, the projections on the other part fitting into said groove, a plurality of tangentially-disposed helical springs, and spring seats for said springs provided with means engaging one of said parts to prevent lateral displacement of said springs, the other of said parts adapted to engage said springs to prevent said spring seats from disengaging said one part.

11. A resilient driving connection comprising a hub member, a rim member surrounding said hub member and provided with a circumferential groove therein, and connecting means interposed between said hub and rim members for resiliently joining the same, said connecting means embodying a lug adapted to engage said groove to prevent unintentional displacement of said connecting means.

12. The combination with a resilient driving connection comprising a hub member having a plurality of radial projections, a rim member having radial projections adapted to coöperate with said hub projections to form pockets therebetween, helical springs tangentially disposed in said pockets, and seats for said springs adapted to engage said rim member to prevent unintended displacement of said springs, said springs being removable by a device inserted between said spring and said rim member, having means to force said spring radially inward, and means to engage said spring seats to move the same laterally, said springs and seats being held in radially-innermost position during said lateral move- 115 ment.

13. The combination with a resilient driving connection comprising a hub member having a plurality of radial projections, a rim member having radial projections adapted to coöperate with said hub projections to form pockets therebetween, and resilient connecting means for joining said hub and rim members disposed in said pockets and held in place by engagement with said rim member, said resilient connecting means being removable by moving the same radially inward and then laterally.

14. The combination with a resilient driving connection comprising a hub member

4
having a plurality of radial projections, a rim member having radial projections adapted to coöperate with said hub projections to form pockets therebetween, and 5 resilient connecting means for connecting said hub to said rim member, said connecting means being removable from said pockets by a tool having a tapered blade adapted to be inserted between said resilient 10 connecting means and said rim to disengage the same, and a lug for moving said resilient connecting means laterally.

15. In a driving connection, the combination with a rim member and a hub member having angularly-spaced interfitting radial parts, of means in the spaces between said interfitting parts for operatively connecting said members, one of said members having one or more annular grooves adapted 20 to receive portions of said connecting means to restrain lateral movement of the latter.

16. In a resilient driving connection, the combination with a rim member and a hub member having angularly-spaced interfitting radial parts, of means in the spaces between said interfitting parts for resiliently connecting said members, said connecting 25

means comprising springs and seats for the springs having lugs, one of said members 30 being recessed to receive said lugs to restrain movement of said connecting means laterally with relation to said rim and hub members, said lugs being withdrawable from said engagement with the recessed 35 member by forcing the springs radially inwardly.

17. In a resilient driving connection, the combination with a rim member and a hub member having angularly-spaced interfitting 40 radially-projecting parts, of means in the spaces between said interfitting parts for resiliently connecting said members, said connecting means comprising helical springs and seats for the springs having lugs, one 45 of said members having annular grooves therein disposed parallel to, and on opposite sides of, the radially-projecting parts thereof, said grooves being adapted to receive the lugs on said spring-seats to restrain the 50 lateral movement of the resilient connecting means.

In testimony whereof I have hereunto subscribed my name this 29th day of Sept. 1916.

GEORGE M. EATON.
